(57) **CLAIM**

The ornamental design for an ejaculation promotion apparatus, as shown and described.

DESCRIPTION

FIG. 1 is a perspective view of an ejaculation promotion apparatus removed from within a container according to the invention;

FIG. 2 is a front elevation view of the ejaculation promotion apparatus of FIG. 1;

FIG. 3 is a rear elevation view of the ejaculation promotion apparatus of FIG. 1;

FIG. 4 is a left side elevation view of the ejaculation promotion apparatus of FIG. 1;

FIG. 5 is a right side elevation view of the ejaculation promotion apparatus of FIG. 1;

FIG. 6 is a top plan view of the ejaculation promotion apparatus of FIG. 1;

FIG. 7 is a bottom plan view of the ejaculation promotion apparatus of FIG. 1;

FIG. 8 is a cross-sectional view of the ejaculation promotion apparatus through line 8-8 shown in FIG. 2;

FIG. 9 is a perspective view of a container with the ejaculation promotion apparatus of FIG. 1 stored within; and,

FIG. 10 is a cross-sectional view of the container and the ejaculation promotion apparatus shown in FIG. 9.

The broken line disclosure, as well as line shading in parts of the drawings is included for the purpose of illustrating use and environment and forms no part of the claimed design.
